UNITED STATES PATENT OFFICE

2,005,733

HEAT EXCHANGE APPARATUS

Crosby Field, Brooklyn, N. Y., assignor, by mesne assignments, to Flakice Corporation, Wilmington, Del., a corporation of Delaware

Application July 14, 1928, Serial No. 292,631
Renewed January 11, 1933

96 Claims. (Cl. 62—105)

This invention relates to a method of manufacturing and an apparatus for manufacturing congealed fluids, and to the product produced by said method, illustrated in the following description of the structure and operation of a heat exchange apparatus of the type in which a coating of brittle material is formed upon and subsequently removed from a deformable member through which the exchange of heat occurs for causing the brittle material to form thereon. In its present employment the invention relates also to ice-making apparatus wherein the ice is formed upon a thin flexible sheet, such as a cylinder, which is subsequently flexed to cause cracking and/or peeling of the ice therefrom. In my patents, Numbers 1,451,901 and 1,451,903 granted April 17th, 1923 there are shown certain forms of cylindrical ice-making apparatus which have proved satisfactory for their intended purposes. It is an object of the present invention to provide improved process and apparatus of this type which will be more particularly suitable for exacting commercial operating requirements and which is useable to produce a product superior to that produced by the machines disclosed in said patents.

The nature and further objects of the invention will be apparent to those skilled in the art from the following description and accompanying drawings of one illustrative embodiment of such apparatus.

In the drawings:

Fig. 1 is a side elevation of such a machine assembled, certain parts included in the cylinder deflecting mechanism being omitted but shown in their proper relationship in other views;

Fig. 2 is an end elevation of a detail shown at the right end of Fig. 1;

Fig. 3 is a partial plan view of the left end of the assembly;

Fig. 4 is a left end elevation, based on Fig. 1;

Fig. 5 is a longitudinal central vertical section;

Fig. 6 is an axial section through the cylinder taken principally on the line 6—6 of Figs. 7 and 8;

Fig. 7 is a transverse vertical section taken on the line 7—7 of Figs. 5 and 6;

Fig. 8 is a transverse vertical section taken on the line 8—8 of Figs. 5 and 6;

Fig. 9 is an enlarged vertical section of the bearing shown on the right of Fig. 5;

Fig. 10 is a transverse vertical section taken on the line 10—10 of Fig. 9;

Fig. 11 is an enlarged perspective view of the cylinder deflecting mechanism;

Fig. 12 is another enlarged view showing in plan

certain details found in the right upper corner of Fig. 11;

Fig. 13 is a horizontal section through the gear case found in the lower portion of Fig. 11; and

Fig. 14 is a vertical section taken on the line 14—14 of Fig. 13.

The present apparatus in general comprises a thin flexible cylinder journaled for rotation within a vessel filled with enough water to cover the cylinder. By the term "cylinder" as herein used, I refer to that connotation which defines a cylinder as generated by a line travelling about any closed curve and constantly remaining parallel to itself, in contradistinction to that connotation which limits the cylinder to one generated by a line moving about a circle and remaining parallel to itself. Brine or any other suitable refrigerating medium is circulated through the interior of the cylinder and forced in jets against its inner surface causing ice to form very rapidly upon its outer surface. At a predetermined time the thin flexible walls of the cylinder may be deflected by suitable mechanism progressively to alter the normal radius of curvature, which peels the ice sheet therefrom and permits a new layer to be formed directly thereon. The ice peeled from the cylinder floats to the surface of the water where it is removed.

Such apparatus avoids the necessity of freezing through a thick wall of initially formed ice as well as the necessity of employing heat for the removal of the ice when formed which are incident to the usual block freezing apparatus and thus obviously accelerates and reduces the cost of production.

As will be hereinafter described I may also operate my apparatus to permit "under-flow" or "freezing-under", as described in my Patent No. 1,480,382, whereby the freezing is further accelerated. With this mode of operation the walls of the cylinder are preferably constantly maintained in a deflected condition.

Foundation and tank

At the bottom of Figs. 1 and 4 are shown foundation skids 20, 20 which support the entire machine. An open-topped tank (see also Fig. 5) is supported upon these skids through its vertical end walls 22, 22 which are reinforced along their marginal edges by angle bars 24. To the inner facing sides of these end walls, there is secured as by brazing or welding a U-shaped sheet 26, the bottom of which is curved to conform generally to the shape of the cylinder to be placed therein and to avoid angular corners 55

which would be difficult to keep clean. The top horizontal edges of the sheet 26 are strengthened by longitudinal beams 28, 28.

5 Removable cylinder assembly

As shown most clearly in Figs. 3, 4 and 5 the end walls 22 of the tank are cut away from their top edges and between their side edges (the top angle bars also being cut) to provide open U-shaped slots 30, 30 for the reception of bored hubs 32, 32 formed integral with the vertically extending bearing supporting plates 34, 34. The plates 34 are larger than the slots 30 so as to overlap the side and bottom edges thereof and are secured against the interior faces of the end walls 22 by cap screws 36. Interposed between the tank end walls and the bearing supporting plates are gaskets 38 which may be in the form of rubber tubing to prevent leakage.

10 Referring to Fig. 5, these hubs 32 form surrounding bearings for hollow stub shafts 40, 40 attached at their inner ends as by set screws 42 to the hubs 45 of disc-shaped heads 44, 44 which close the ends of and rotatably support a cylinder 15 of thin flexible material generally indicated by the numeral 46. The space between each shaft and its bearing may be sealed by packing 48 placed in an annular recess in the bearing hub and held by a flanged packing gland 50 adjustably secured 20 to the bearing plate 34 by set screws 52.

25 Cylinder construction

As shown in Figs. 5 and 6, the cylinder, for 30 various constructional and operating desiderata, is preferably made up of a plurality of thin edge-to-edge arranged sheets 54 of a metal having substantial flexibility and strength which are secured together by interior circumferential strips 56 of fabric-reinforced rubber and a longitudinal strip 58 of the same material. The outer ends of the cylinder thus formed are provided with other fabric-reinforced rubber aprons 60 which are secured to the heads 44 by wire strands 62 wound over the thin ends of the aprons 60 to bind them into circumferential 35 grooves 64 formed in the heads. The strips 56 and the end aprons 60 are considerably thickened beneath the metal sheets for the dual purpose of providing heat insulation to prevent formation of ice beneath the edges of the metal 40 sheets which would tend to separate the metal from the rubber and of providing tracks for cylinder deflecting rollers presently to be described. In manufacturing a cylinder such as 45 described above the following steps known to the man skilled in the art may be followed. A collapsible mandrel is provided areas of the outer surface of which are covered with forms of rubber or other suitable material coinciding with the uncovered portions of the metal panels of 50 the finished cylinder. The space between the forms is partially filled with "gum" or raw rubber over which is placed a "frictioned" fabric. (Under certain circumstances it is advisable to rub the "frictioned" fabric with a solvent such 55 as benzol before covering it with the raw rubber.) Then a layer of the "gum" rubber is placed over the "frictioned" fabric to fill completely 60 the space between the forms.

70 The surfaces of the panels which are to be cemented to the rubber are sanded and cleaned and coated with thermo-plastic cement such as "Vulcalock." This cement is of course allowed to dry and is further coated with a steam-curing cement. The panels are then placed over 75 the mandrel and to hold them in position a wet

canvas cloth is wrapped around the outside of the panels, which cloth on drying shrinks and presses the panels tightly against the mandrel and the raw rubber.

The whole assembly is then subjected to the known vulcanizing treatment wherein it is subjected to about 20 pounds of steam for about 20 minutes.

10 Cylinder driving mechanism

As shown in Figs. 1 and 5, the stub shafts 40 are equipped with sprocket wheels 66 fast thereon which are geared by sprocket chains 68 to sprocket pinions 70 and 71 mounted on a jack shaft 80 at the left and right ends respectively of the machine, the jack shaft being rotatably mounted in bearing boxes 81 fixed to the side of the tank by bolts 82.

The cylinder may be successfully driven from one end only but the provision of a drive sprocket for each end of the cylinder serves to equalize the driving torque on the cylinder and gives more satisfactory operation. Further to insure this equalization one of the sprockets—71 as shown in Figs. 1 and 2—is made adjustable on the jack shaft 80. This is accomplished by mounting the sprocket 71 loosely on the shaft adjacent a fixed hub 73 and providing the sprocket with arcuate slots 75 which bolts 77 passing through holes in the hub 73 are adapted to enter to clamp the sprocket in various adjusted positions to the hub and jack shaft.

The jack shaft 80 may be driven, as shown at the left of Fig. 1 and in Fig. 4, by a sprocket chain 83 operating upon a sprocket 84 fast on the shaft 80 and another sprocket 86 fast on the low speed shaft 88 of a reduction gear train housed in the casing 90, the high speed shaft 92 of which is driven by a motor M. Both the motor and gear casing are mounted on transverse channel beams 94 supported on the skids 20, the base of the motor being mounted directly on the beams 94 while the gear casing is mounted on intermediate edge-supported channels 96 which, in turn, are carried upon the beams 94.

Preferably (Fig. 4) the high speed shaft 92 of the gear train is connected to the motor shaft 98 by a flexible coupling 100. Conveniently, the other end of shaft 92 may be employed for operating a brine pump 104 through a similar flexible coupling 106, the pump also being supported upon the transverse beams 94 by a plate 108.

The parts thus far described are sufficient for the observation that if the cylinder is submerged in water filling the tank to some point P, indicated by a wavy line in Fig. 5, ice will be formed from the water upon the outer surface of the cylinder if a cold-producing medium be circulated through the interior of the cylinder. And further, that since the cylinder is capable of rotation upon its own axis, the brine may be directed to all points along its interior surface by fixed nozzles if desired. The mechanism for circulating brine through the cylinder will now be described.

65 Brine circulating system

As shown in Fig. 5, brine is led into and from the interior of the cylinder by a tube 110 extending from end to end through the cylinder 46 and its hollow shafts 40. This tube is held from rotation in any suitable manner as, for example (see the left side of Fig. 5 and Fig. 4) by a yoke 112 embracing and attached to a torque collar 114, at its upper bifurcated end and at-

tached to a fixed part, for example one of the channels 96 supporting the gear casing 90, at its lower end by a bolt 120. The collar 114 may be secured to the tube 110 by set screws 116. Provision is made for preventing leakage along the tube 110 both between the tube and the stub shafts 40 of the cylinder and between the tube and the interior of the hubs 45 of the cylinder heads 44. Since the parts at one end of the tube have counter-parts at the other end, only one end need be described.

Referring to the right end of Fig. 5 and to Fig. 9, the tube 110 is reduced within the hollow shaft 40 and the latter is provided with an internal annular rib 122 against which packing 124 is pressed by a gland 126 screwed into the outer end of the shaft. Fitted between the flange of the gland 126 and the end of the shaft 40 are shims 128 to furnish firm axial coordination between them since the flange has a further function in a thrust bearing assembly. In making adjustments on the packing, if a shim is removed from one side of the flange a shim of the same thickness is inserted on the other side to keep the bearing assembly in proper position.

The tube is further surrounded by a bearing bushing 130, preferably of lignum vitae, set into an annular recess in the outer end of the packing gland 126. The bushing 130 is held by a washer 132 disposed on one side of a ball thrust bearing 134, the bearing at its other side acting through a similar washer 132 against a thrust collar 136 (at the left end, torque collar 114 already described serving the same purpose) rigidly secured to the tube.

Returning to Fig. 5, within the hub 45 the tube 110 is provided with a bushing 138 of non-corrodible material, for example nickel, and the hub carries a lignum vitae bearing bushing 140 closely fitting the nickel bushing and held to the hub by set screws or equivalent means.

Referring to Figs. 3 and 4 and the left ends of Figs. 1 and 5, cold brine is forced into the tube 110 by the pump 104 having an intake pipe 142 and a discharge pipe 144. The discharge pipe 144 extends upwardly from the pump and is bent at its upper end to connect with a flexible coupling 146, which, in turn, connects with an elbow 148 attached to the upper end of an enlarged stand-pipe 150. The stand-pipe includes and is supported by a T-coupling 152 threaded upon the open end of the tube 110. Brine flowing into the stand-pipe enters a concentric strainer 154 (Fig. 5) and flows through it into the surrounding annular space and thence into the tube 110.

The lower end of the stand-pipe is closed by a cap 156 provided with a quick-throw dump valve 158 having a handle 160 for discharging collected sediment. If desired the portion of the stand-pipe below the T-coupling may include a transparent glass cylinder 162 for visual determination of the amount of sediment collected. The glass cylinder may be held between the T-coupling and the cap 156 by clamp bolts 164 which serve also to protect the glass against breakage.

It is desirable to maintain a sufficient brine pressure within the cylinder 46 so that it cannot be collapsed by the hydro-static pressure of the water normally contained in tank 26. Normally when the machine is in operation and the pump is working sufficient pressure is maintained within the cylinder but since the pump preferably

employed is of the centrifugal type there may be a back-flow of liquid therethrough when the pump is not working. This back-flow would create a siphon to draw brine from the cylinder if no means were provided to permit air to flow into the upper part of the brine supply line including the elbow 148, the flexible coupling 146 and the upper portion of the pipe 144. For the purpose of preventing formation of such a siphon the stand-pipe 150 near its upper end is provided with a short pipe 166 equipped with an inwardly opening check valve generally indicated by the numeral 168. The check valve is designed to open and permit the inflow of air whenever the pressure within the stand-pipe 150 becomes less than atmospheric. Thus the brine cannot be withdrawn from the cylinder 46 to a level lower than the pipe 166 if the discharge stand-pipe at the other end of the machine to be described hereinafter is as high as the pipe 166.

It is evident from the foregoing description that stationary tube 110 extending co-axially through the working cylinder constitutes the means for the feed and discharge of brine therefrom; that this tube is carefully sealed from surrounding parts both to prevent leakage and to prevent formation of ice at undesired points; that brine is supplied to the left end of the tube through a strainer by a pump operated by the motor through a flexible shaft; and that the pipe 166 equipped with valve 168 prevents the siphoning of brine from the cylinder. Overflow from the upper end of the discharge stand-pipe presently to be described prevents the building up of excess pressure within the cylinder. An explanation will now be given of the manner in which brine from the central tube is sprayed against the interior surface of the rotating cylinder and the spent brine removed from the cylinder.

At the left central portion of Fig. 5 and in Fig. 7 the tube 110 is seen to be provided with four circumferentially spaced threaded holes for the reception of four nipples 170 and the tube is closed immediately beyond these holes by a plug 172 which is formed with end-opening recesses 174 positioned beneath the holes in the tube for dividing the incoming supply of brine into four equal streams flowing through the nipples 170 to four circumferentially spaced points within the cylinder.

Each tube nipple 170 is connected by a flexible heat insulating sleeve 176 with a trough nipple 178 formed integral with or rigidly secured to the bottom of a metal trough 180 closed at its ends and extending longitudinally along the greater part of the length of the cylinder.

Opposite the end of the nipple 178 is secured a baffle plate 182 for deflecting along the trough the brine flowing from the nipple.

Closing the outer open side of the trough 180 is a foraminous metal plate 184, the greater portion of the surface of which is formed on the arc of a circle of smaller radius than the normal radius of the cylinder. A spray or jet of brine is intended to be projected through the small holes of the foraminous plate against the interior surface of the cylinder, hence the plate is located closely adjacent thereto but sufficiently distant to permit the normal curvature of the cylinder to be altered to the desired extent for peeling ice therefrom. When positioned close to the cylinder the plates are capable of forming supports for the cylinder to prevent injury there-

to in case for any reason the cylinder should collapse.

- Desirably each trough may be partially covered by a heat insulating back 186 attached to the 5 curved outer edges of the plate 184. This back may be formed of felt if suitably strengthened as by a wire screen of non-corrodible material. The entire spray trough assembly is supported in peripheral notches 188 of spaced spiders 190, 10 190, fastened upon the tube 110 by set screws 192 passing through their hubs 194, the spiders being provided with a plurality of apertures 196 for the free circulation of spent brine through the cylinder.
- 15 Spent brine escapes from the cylinder into the right hand end of the tube 110 by way of discharge openings 198 formed therein and flows from the end of the tube into a discharge stand-pipe 200, the latter emptying into any suitable 20 disposal system, for example, a recooling system (not shown) supplying the intake pipe 142 of the brine pump 104, care being taken that undue back pressure will not be created in the stand-pipe and that a siphon will not be formed which might 25 drain all of the brine from the cylinder.

Mechanism for deflecting the cylinder to peel ice therefrom

It is clear from the foregoing description that 30 the cylinder rotates past the jets of cold brine issuing from the small holes in the spray plates 184 which causes a continuous layer of ice to form on the metal sheets of the cylinder. This ice formation clings to the cylinder with great tenacity 35 so long as the cylinder retains its normal shape but is readily removed in sheets or flakes which float to the surface of the water in the tank if the cylinder is deflected sufficiently from its normal shape. Means is herein provided for producing 40 a substantially uniform deflection of the cylinder across its entire width and this means is so designed that the deflection may occur in timed relationship with the operation of the cylinder for producing ice flakes of predetermined 45 thickness, it being understood that the deflection of the cylinder may be so controlled as to break the ice and free it completely from the cylinder or so as merely to cause local separation between the ice and the cylinder so as to permit 50 under-flow or under-freezing as disclosed in my Patent No. 1,480,382, granted January 8, 1924.

As described in the above-mentioned patent, under-flow or under-freezing refers to the method of freezing ice which consists in separating an ice 55 sheet or strip formed on a freezing surface from the freezing surface and allowing liquid being frozen to enter into the space between the sheet and freezing surface so that immediate transfer of heat from the liquid through the surface takes 60 place, congealing the liquid and freezing the sheet to the surface. In this way, an ice layer or sheet is built up on the freezing surface. As I pointed out in my patent No. 1,480,382, I prefer to accomplish this freezing on a surface which is maintained 65 constantly deflected and accordingly in the present embodiment when the machine is operated to permit under-flow or under-freezing, I prefer to control the deflection of the cylinder in such a way as to maintain it in a state of constant deflection.

This mode of operating my apparatus to cause under-flow or under-freezing will be described in greater detail hereinafter.

Alternatively the deflecting means may be controlled by hand for producing flakes of any thick-

ness desired by the operator. This deflecting mechanism, in its illustrated embodiment will now be described.

In Figs. 6 and 8 the deflecting means or ways are shown as a plurality of rollers 206 closely mounted upon the shafts 208 and held in the required axial position thereon by fixed rings 210 on the ends of the shafts, washers 212 between the roller hubs and supporting sleeves 214 carrying the shafts. There are (Fig. 8) four such 10 shafts 208 and four sets of rollers.

The rollers of each set are formed with flanges 216 normally spaced slightly from but adapted at certain times to operate upon the thickened portion of the cylinder joint strips 56 and end aprons 15 60. The rollers are designed to have radial movement for pressing the cylinder outwardly across its entire width along four circumferentially spaced lines thus changing it from a cylinder to an approximately quadrilateral figure having 20 four principal surfaces (between rollers) having a supernormal radius of curvature joined by four smaller surfaces (over the rollers) having a subnormal radius of curvature.

From the above it is clear that the rollers or 25 ways 206 are capable of deflecting the cylinder uniformly across its entire width. In this connection the aprons 60 which are employed for driving and supporting the cylinder 46 by means of the heads 44 co-operate with the deflecting 30 rollers or ways 206 to permit the cylinder to be deflected uniformly across its entire width, by permitting radial movement between the cylinder panels 56 and the heads 44.

For producing this radial movement of the 35 rollers the shaft-carrying sleeves 214 are formed integral with slides 218 operating upon radial guide rods 220 affixed at their inner ends to the hubs 194 of the spiders 190 previously described. The slides 218 are spread or retracted by links 222 40 pivoted thereto at their outer ends and pivoted to arbors 224 at their inner ends. The arbors 224 are positioned within the tube 110 and have axial movement which is translated by the links 222 into radial movement of the slides, the action 45 being analogous to the opening and closing of an umbrella. It is necessary, therefore, to provide longitudinal slots 226 in the tube 110 for passage and movement of the links 222. The links may be initially adjusted as to length by provision of 50 an externally threaded stem portion 222a entering an enlarged, internally threaded socket portion 222b. This adjustment provides one of the means by which it is possible to control or vary the amount of deflection of the cylinder wall 55 caused by the rollers 206 for purposes to be described hereinafter.

Within the tube 110 the axially slidable arbors 224 (Fig. 6) are fixed upon a reciprocatory deflector rod 228 guided for longitudinal movement within tube 110 by the plug 172, previously mentioned, and guided at the left end by a stuffing box 230 (Figure 5) formed on the outer side of the T-coupling 152 into which the left end of tube 110 is threaded. The stuffing box 230 is 60 provided with rod packing held in place by a gland 234 and the plug 172 is provided at the right end with rod packing 232.

Means is provided for producing reciprocatory movement of the deflector rod 228. As best shown 70 in Fig. 11 but shown also in Fig. 3, the outer end of deflector rod 228 is provided with vertically aligned stud pins 236 each taking into the end of a split lever 238 which is pivoted intermediate its ends upon an apertured block 240 adjustably 75

held on an eye-bolt 242 by adjusting nuts 244. The eye-bolt 242 is pivoted between spaced lugs 245 integral with the T-coupling 152. The other end of the split lever 238 is pivoted to the left end of an axially reciprocable bar 246 supported intermediate its ends between rock arms 248 pivoted upon the tube 110 by set screws 250. If the bar 246 is moved to the right it will move the deflector rod 228 to the left to move the rollers 206 radially outward and if the bar is moved to the left it will move the rod 228 to the right to move the rollers radially inward.

This connection between the bar 246 and the deflecting rod 228, affords a second adjustment for controlling or determining the amount of deflection of the cylinder wall caused by the rollers 206.

As herein illustrated cams and associated mechanisms are employed for imparting properly timed endwise movements to the bar 246 and the deflector rod 228. The cams are shown in Figs. 3, 5 and 11 to comprise a retracting cam 252 attached to the outer side of the flange of the left packing gland 126 and a distending cam 254 attached to the inner side of this flange.

Since the deflector mechanism tends to remain in its retracted position, the retracting cam 252 (Fig. 5) is formed merely with an axially inclined ramp face extending over about half of a revolution. In operation, the cam carries its follower axially past the high point of the ramp there to stay until such time as it is moved in the opposite direction.

On the other hand, the deflector mechanism when distended tends to return to retracted position due to the resiliency of the cylinder; hence the distending cam 254 (Figs. 1, 3 and 5) is formed with an axially inclined ramp 254a which extends over about one revolution and which flattens out at its high point into a level annulus 254b set back below the bottom wall of the ramp. A follower if urged toward the axis of rotation of the cam will ride up the inclined ramp, being moved axially to the right by this action, and upon reaching its apex will move inwardly upon the flat annulus and thereafter rides upon the flat annulus until released.

The parts for operatively connecting the shaft cams 252, 254 to the bar 246 are as follows. As shown in Figs. 11 and 12 the reciprocatory bar 246 is provided with spaced transversely moving cam followers 256, 258 operating in guides 260 fixed to the bar 246, each follower carrying a loose cam roller 262 and the one—256—cooperating with the retracting cam 252 while the other, 258 cooperates with the distending cam 254. The followers 256, 258 are provided with slots 264 receiving the rounded ends of a rocking lever 266 pivoted centrally upon a clip 267 attached to the bar 246, the lever in turn being keyed to and oscillated by a rock shaft 268 associated with suitable timing mechanism.

When the shaft 268 is turned in one direction it causes one of the followers 256 or 258 to be pressed toward its associated cam and when turned in the other direction it withdraws the one follower and causes the other to be pressed toward its associated cam, engagement of the cam followers with their cams causing the bar 246 to be reciprocated either to the right or to the left.

In Fig. 11 the rock shaft 268 is seen to be operatively connected to a lower rock shaft 270 through a torque spring 272 provided with a cuff 274 at its upper end rigidly attached to the shaft

268 and with a castellated coupling 276 at its lower end meshing with a similar castellated coupling 278 adjustably fixed to the shaft 270 by a set screw 280. The coupling 278 may either be moved up and attached to the shaft 270 so as to mesh with coupling 276, as shown in the several views for power operation of the shaft 268 and the cam followers, or it may be moved down the shaft out of mesh with the coupling 276 for manual operation of the shaft 268 and the cam followers. A handle 282 is provided on the coupling 276 for manual operation.

From the foregoing it is clear that when the coupling 278 is moved down and out of mesh with the coupling 276, the rollers 206 may be set for permanent deflection of the cylinder walls in the following manner: While the cylinder 46 and the stub shaft 40 are rotating, the handle 282 connected through the torque spring 272 to the lock shaft 268 is moved counterclockwise, thereby forcing the cam follower 258 into the path of the distending cam 254. With this operation the cam follower 258 rides up the axially inclined ramp of the distending cam for one revolution of the stub shaft 40 until it reaches the end of the ramp 254 whereupon continued counterclockwise pressure on the handle 282 forces the cam follower 258 onto the flattened level annulus or cam 254b. The handle 282 is now released, leaving the cam follower 258 in its forward position and in contact with the annulus 254b. It is thus clear that the lever 246 has been moved to the right with this operation (Figure 1) and is held permanently at its right hand position by the cam and cam follower and that the deflector rod 228 has been moved to its left hand position, thereby forcing the deflecting rollers 206 into their deflecting position to cause a constant state of deflection of the cylinder wall as it rotates.

As hereinbefore pointed out, when the apparatus of the present embodiment is operated to permit under-flow or under-freezing, it is preferable to maintain the cylinder walls under constant deflection. As pointed out in my patent, No. 1,480,382, the deflection of the walls is preferably obtained by adjusting the deflecting rollers (in the present embodiment, rollers 206) so that they exert the desired pressure against the cylinder wall at diametrically opposite points to obtain the desired constant deflection thereof. In the present embodiment this desired pressure is obtained by following the same procedure, i. e., by adjusting the toggle mechanism 222 and the connection between the lever 246 and the deflecting rod 228. Then by moving the cam follower 258 into contact with the cam 254b (as hereinbefore described) the rollers 206 are moved into deflecting position. Now, when the cylinder 46 is rotated while submerged in the liquid being frozen, and the refrigerating agent is circulated through the cylinder, each unit portion of the wall is flexed from its normal confirmation four times during a complete revolution of the cylinder.

As described in my patent, No. 1,480,382, with this deflection, it will be understood that a limited section of the cylinder wall, as it approaches each of the pressure rollers or ways 206, is deflected and separates from the inner face of the ice layer, thereby providing a space between the ice layer and the wall extending across the entire width of each panel of the cylinder and open at its opposite ends so that water in the tank may enter between the ice film and the flexible cylinder wall. Thus there is continuous contact

of the water directly with the wall of the cylinder adjacent each roller and consequently an immediate transfer of heat from the water entering the space. As the cylinder continues to 5 rotate at least a part of this water is converted into ice crystals which are added to the ice layer on its inner face, and which bind the separated ice layer to the cylinder wall.

As this limited section now passes over the 10 next successive roller, the under-freezing process is repeated; and so on at the successive rollers until the ice sheet forming on the wall becomes so inflexible as compared with the degree 15 of deflection of the cylinder wall that the separation between the ice sheet and the cylinder wall becomes too great to permit the under-flow or under-freezing, and the ice sheet peels from 20 and is projected from the panels of the cylinder in successive elongated symmetrical sheets or strips.

Summarizing this mode of operation in another way, I position the ways 206 to cause the cylinder wall 46 to travel about a predetermined path, the path being such that as the cylinder 25 wall passes over a portion thereof, congealing of the liquid on the cylinder wall takes place without a complete separation therefrom. However, over the remaining portion of the path, the cylinder wall is so deflected that the ice peels 30 therefrom in sheets.

When the apparatus of the present invention is operated to permit under-flow or under-freezing, according to the manner described in my patent, No. 1,480,382, new and useful results are 35 obtained not obtainable with the apparatus shown therein. For example, with the present apparatus in which each panel or sheet 54 of the cylinder 46 is deflected uniformly across its entire width by the deflecting rollers 206, the sheets 10 or strips of ice formed on the respective panels 56 are separated and peeled from the panels without any breakage along the longitudinal axis of the sheets. Further, by constructing the cylinder 46 to provide parallel peripheral insulating areas between the panels 56, the sheets of 15 ice formed on the panels have parallel edges. Thus, the successive ice sheets peeled from the panels, when the cylinder is operating under freezing-under conditions, are substantially 20 symmetrical with respect to each other and have at least two parallel edges.

However, the cylinder construction and the deflecting mechanism as disclosed in my patent, No. 1,480,382, is such that the cylinder wall is 25 not deflected uniformly across its width. The deflecting mechanism causes the cylinder wall to be deflected more in the central portion thereof than in the side or end portions thereof, thereby causing a bulge in the central portion. Consequently, when the apparatus described in my 30 afore-mentioned patent is operated to permit freezing-under the ice sheet formed on the cylinder is materially fragmented along its central and other portions, and the ice does not come 35 off the cylindrical wall in the form of successive symmetrical elongated sheets, but in the form of irregular fragments varying not only in surface area but in thickness due to the fact that the non-uniform flexing of the cylinder 40 sometimes causes incomplete freeing of the ice 45 leaving some portions on the cylinder.

Under certain other conditions of operation, I may prefer to form an ice layer on the cylinder while the cylinder wall is not deflected and 50 then subsequently change the path of the cylinder 55

to deflect the walls sufficiently to cause the ice sheet formed thereon to crack and peel from the cylinder. For this purpose the afore-mentioned timer mechanism is employed which comprises, as shown in Figs. 11, 13 and 14, a cam disc 284 rotatably mounted within a casing 286 (attached to gear casing 90) and constantly driven by a worm 288 on the outer end of the low speed shaft 88, previously mentioned. This shaft with its worm exposed is also shown in Figs. 1 and 5. 10 The shaft 270 is provided with a spherical enlargement 271 operating in a similarly shaped bearing in the casing 286 and at its lower end carries an arm 290 supplied with a cam stud 292 operating in a cam groove 285 formed in the 15 upper face of the disc 284. The cam groove includes a relatively long inner retracting portion 285a and a relatively short outer distending portion 285b.

By the construction just described it is apparent that the retracting cam follower 256 is pressed against its associated retracting cam 252 and the bar 246 is held toward the left for a relatively long period of time while the cam stud 292 is riding within the long retracting portion 285a 25 of the cam groove 285 and that the distending cam follower 258 is periodically pressed against its associated distending cam 254 and the bar 246 is held toward the right for a relatively short period of time while the cam stud 292 is riding 30 within the short distending portion 285b of the cam groove 285; that the torque spring 272 and the universal bearing provided for the lower shaft 270 maintain an operative connection between the parts in all positions of the bar 246; and further that the mechanical timing mechanism may be completely disconnected and the action of the deflecting mechanism timed by hand.

Heat insulation and ice scrapers for heads of cylinder

In the operation of the machine there is a tendency for ice to form on the outer faces of the cylinder heads 44 and this ice might eventually build up until it filled the spaces between the 45 rotary heads and adjacent stationary parts. Further, there is a tendency for ice to form upon the end aprons 60 of the cylinder where they are attached to the heads 44 on account of the small amount of flexing imparted to the aprons adjacent these fixed lines of attachment. Formation of ice over the aprons would still further decrease their permissible flexing and impair the efficiency of the machine. Means is herein provided for avoiding these difficulties so as to keep 50 the machine in proper operating condition for any length of time it may be used.

In Figs. 5 and 6 each cylinder head 44 is seen to be equipped on its inner face and beneath the end apron 60 with a plurality of discs 294 of heat 60 insulating material such as sponge rubber, beveled on their outer edges to form a flexible seal with the apron in all of its movements. The discs may be held in position by a metal shield 296 and screws 298 entering threaded holes in the head. 65

There is also a slight tendency in spite of the insulating discs 294 and further hub cuffs 295 for cold to travel along the hub 45 of the cylinder head and form ice on the outer surface of the head near its axis. This formation of ice takes 70 place quite slowly and may conveniently be removed with scrapers.

Referring to Figs. 5 and 10 the flange of packing gland 50 is provided with radially inclined ice scrapers 304 and 306 facing the end of the rotat- 75

able cylinder head. The leading scraper 304—
considered with respect to the direction of rota-
tion of the cylinder head—is serrated to cut an-
nular grooves in the ice while the trailing scraper
5 306 has a straight edge to shave off the ridges left
between grooves. By operating in this manner it
has been found that the ice formation can be re-
moved with much less expenditure of power than
10 if either serrated or straight scrapers alone were
used.

Air vent for cylinder

15 Due to the constant presence of air in most
bodies of fluid there is a likelihood of the top of
the closed cylinder becoming the collection point
for a body of air which would prevent brine from
20 contacting the entire interior surface of the cylin-
der and hence reduce the efficiency of the ma-
chine. To forestall this (Figs. 5 and 8) a flexible
air vent tube 308 is provided and has an opening
25 near the upper inner surface of the cylinder where
air would collect for conducting it out of the
cylinder in any suitable way.

As shown, the tube 308 embraces the end of a
25 nipple 310 screwed into the deflector rod 228 and
operating within a slot 311 in the tube 110. The
rod 228 is formed with a small bore 312 for con-
ducting the air to the left end of the rod where it
30 may be withdrawn by a hand cock 314, clearly
shown in Figs. 3 and 4.

Ice collection

35 Ice removed from the cylinder and floating to
the surface of the water in the tank may be re-
moved in any approved manner. The mechanism
herein provided for this purpose is shown in Figs.
1, 4 and 5, and comprises spaced endless flexible
40 members such as conveyor chains 320 carrying
blades 322 and passing obliquely from sprockets
324 on a lower shaft 326 to sprockets 328 on an
upper shaft 330. The blades 322 beneath the
45 lower shaft dip below the surface of the water
and gather ice ahead of them pushing it up an
inclined drainage ramp 332 over the upper edge
of the tank and pass it to a discharge chute 334.

50 The ice peeling from the cylinder 46 may be
broken into fragments by the blades 322 and/or
by falling from the chute 334 to a storage bin or
other receptacle for the ice flakes. The ice flakes
55 formed by the breaking of the successively formed
symmetrical sheets when under-flow freezing is
employed, as hereinbefore described, break into
curved fragments which have a greater uni-
formity in size and shape than fragments formed
from non-symmetrical sheets, and hence are bet-
ter adapted to various commercial purposes than
the less nearly uniform fragments resulting from
the older methods previously described.

60 The ice fragments thus produced, when stored
or packed, remain loose and free-flowing, for,
due to their intrinsic shape, they contact with
each other only over limited areas. Consequent-
ly they do not tend to congeal together.

65 The shafts 326 and 330 are mounted in bearings
carried by transverse inclined beams 336 and the
latter shaft is driven from the jack shaft 80 by a
belt 338 passing over pulleys 340 and 342 fixed to
the shaft 330 and the jack shaft respectively.

Water regulation

70 Since the body of water in the tank is constant-
ly being used up in the formation of ice which
is removed it is necessary to replenish the sup-
ply and it is desirable that the additional water
75 be added gradually and constantly so that the wa-

ter level in the tank may remain substantially
the same at all times.

As shown particularly in Fig. 5 water is sup-
plied at the top of the tank by an inlet pipe 344
controlled by a float controlled valve 346, a well
being provided for the float if desired to protect
it from contact with floating ice.

At another point near the top of the tank an
overflow pipe 348 is located and at the bottom of
the tank a drain cock 350 is adapted to remove
10 all the water from the tank when desired.

15 The operation of the machine will be apparent
from the foregoing description without further
amplification. The machine in operation makes
ice much more rapidly and efficiently than is pos-
sible with the usual types of ice making machines.
Further the machine may be operated for long
20 periods of time without breakage or without stop-
page for any reason. Ice can be made by the
machine in suitable form for immediate use 25
avoiding the usual waste of time and ice entailed
in shaving or cracking smaller pieces from a large
block.

While one specific embodiment of the invention
has been described with particularity it is to be 25
understood that the invention is not meant to be
limited thereby but may have numerous other
embodiments within the scope of the appended
claims.

I claim:

1. Apparatus of the character described, com-
prising in combination, a tank adapted to contain
water, a flexible cylinder rotatably mounted in
the tank beneath the surface of the water, a sta-
tionary axial tube and a longitudinal spray trough
35 providing means to force a jet of cold brine
against the interior surface of the cylinder, and
means for deflecting the cylinder to peel ice
therefrom including a plurality of rollers mov-
able between a retracted position and a distend-
ed deflecting position, an axial deflector rod for
operating said rollers, and mechanism timed with
the operation of said cylinder for actuating said
deflector rod.

2. Apparatus of the character described, com-
prising in combination, a rotary cylinder of thin
flexible material, and deflecting means for said
cylinder including rollers disposed adjacent the
inner surface of said cylinder, and means for dis-
tending and retracting said rollers in timed re-
lationship to the rotation of the cylinder, said
50 roller-distending means comprising radially slid-
able guide members, expansion links connected
to said slidable members, and an axially movable
rod connected to the inner ends of said links.

3. Apparatus of the character described, com-
prising in combination, a rotary cylinder of thin
flexible material, and deflecting means for said
cylinder, including rollers disposed adjacent the
inner surface of said cylinder, and means for dis-
tending and retracting said rollers in timed
relationship to the rotation of the cylinder.

4. Apparatus of the character described, com-
prising in combination, a rotary cylinder of thin
flexible material, deflecting means for said cyl-
inder operable between a first position in which
no deflection of the cylinder is produced and a
second position in which the cylinder is deflected
from its normal configuration, and means con-
trolling the action of said deflecting means to
move it from the first to the second position after
the cylinder has made a predetermined number of
revolutions.

5. Apparatus of the character described, com-
prising in combination, a rotary cylinder of thin

- flexible material, deflecting means for said cylinder operable between a first position in which no deflection of the cylinder is produced and a second position in which the cylinder is deflected 5 from its normal configuration, and means for controlling the operation of said deflecting means.
6. Apparatus of the character described, comprising in combination, a rotary cylinder of thin flexible material and deflecting means for said cylinder operable between a first position in which no deflection of the cylinder is produced and a second position in which the cylinder is deflected 10 from its normal configuration for the purpose set forth.
15. 7. Apparatus of the character described, comprising a flexible cylinder adapted to be deformed to loosen ice formed on the outer surface thereof and spray means within said cylinder acting to project a refrigerant on the inner surface thereof, 20 said cylinder and spray means having relative movement to provide contact by the spray with the entire circumference of the cylinder without interference with the deformation thereof.
8. Apparatus of the character described, comprising a flexible heat transfer cylinder adapted to be deformed to loosen ice formed on the outer surface thereof and a longitudinal spray trough within said cylinder acting to project a refrigerant 25 on the inner surface thereof, said cylinder and spray trough having relative movement to provide contact by the spray with the entire interior surface of the cylinder without interference with the deformation thereof.
30. 9. Apparatus of the character described, comprising a thin flexible heat transfer cylinder, adapted to be deformed to loosen ice formed on the outer surface thereof and a plurality of longitudinal spray troughs within said cylinder acting to project a refrigerant on the inner surface thereof, said cylinder and spray troughs having relative movement to provide contact by the spray with the entire interior surface of the cylinder without interference with the deformation thereof.
40. 10. Apparatus of the character described, comprising a thin flexible heat transfer cylinder and a plurality of approximately rigid longitudinal spray plates arranged about the axis of the cylinder and closely adjacent the interior surface of said cylinder for jetting a spray of refrigerant thereupon and for supporting the cylinder in event of its collapse.
45. 11. Apparatus of the character described, comprising a thin flexible heat transfer cylinder and means for supporting the cylinder in event of its collapse, said means comprising a plurality of circumferentially spaced longitudinal spray plates and similarly disposed deflecting rollers arranged alternately.
50. 12. Apparatus of the character described comprising, a heat transfer cylinder, a spray trough for jetting cold brine directly against the interior surface of the cylinder, a conduit for conducting cold brine into the spray trough, and insulation upon said trough and conduit for keeping them from contact with spent brine within the cylinder.
55. 13. Apparatus of the character described, comprising a freezing cylinder of thin flexible material, heads for said cylinder, and means for minimizing freezing through said heads and the head-attached ends of the cylinder comprising a plurality of flexible-edge insulating discs interiorly attached to the heads and closely fitting within the cylinder.
60. 14. Apparatus of the character described, comprising a freezing cylinder provided with rotary heads and means for scraping accumulating ice from the outer surfaces of the heads, said means comprising a serrated scraping blade and an associated smooth scraping blade.
65. 15. Apparatus of the character described, comprising a rotary freezing cylinder, means for circulating a refrigerant fluid through said cylinder, and means near the top of the cylinder for venting entrapped gases from the interior of said cylinder for the purpose specified.
70. 16. Apparatus of the character described, comprising a rotary freezing cylinder, means for circulating a refrigerant fluid through said cylinder, and means for venting entrapped gases from the 10 interior of the cylinder near the top thereof for the purpose specified, said means comprising a flexible tube opening below the crown of said cylinder and a hollow rod connected to said tube extending to the exterior of said cylinder along its axis.
75. 17. Apparatus of the character described comprising a flexible heat exchange cylinder immersed in a body of water and means for circulating a refrigerating fluid through the cylinder 15 including a stand pipe for maintaining a hydrostatic head on the interior of the cylinder.
80. 18. Apparatus of the character described comprising a flexible heat exchange cylinder immersed in a body of water and means for circulating a refrigerating fluid through the cylinder 20 including a stand pipe for maintaining a hydrostatic head on the interior of the cylinder, and a drain pipe for said stand pipe for preventing formation of a siphon capable of draining fluid 25 from the cylinder.
85. 19. Apparatus of the character described, comprising a thin flexible cylinder formed of a plurality of metal sheets joined by rubber strips.
90. 20. Apparatus of the character described, comprising a thin flexible cylinder, heads for said cylinder, and flexible aprons of heat insulating material for connecting said cylinder to said heads.
95. 21. Apparatus of the character described, comprising a thin flexible cylinder formed of a plurality of metal sheets joined circumferentially and axially by heat insulating strips.
100. 22. Apparatus of the character described, comprising a thin flexible cylinder formed of a plurality of metal sheets joined by circumferentially disposed rubber strips, deflecting rollers disposed within said cylinder and thickened portions formed on said strips adapted to serve as tracks for said deflecting rollers.
105. 23. Apparatus of the character described, comprising a thin flexible cylinder, stub shafts connected with the opposite ends of said cylinder, means to drive both of said shafts together, and adjusting means for equalizing the drive upon the two shafts.
110. 24. Apparatus of the character described, comprising a thin flexible cylinder, stub shafts connected with the opposite ends of said cylinder, means to drive both of said shafts together, and adjusting means for equalizing the drive upon the two shafts, said means including a jack shaft geared to both of said shafts and a circumferentially adjustable driving member on said jack shaft.
115. 25. Apparatus of the character described, comprising a flexible cylinder and deflecting means for said cylinder including a deflector rod, constantly operating means capable of actuating said rod, and means for periodically connecting said rod with said actuating means.

26. Apparatus of the character described, comprising a flexible cylinder and deflecting means for said cylinder including a deflector rod, constantly rotating cams adapted to operate said rod selectively in either deflecting or retracting direction, and means for placing said rod under the influence of said cams, said means including cam followers selectively slidable toward and from the cams and means for operating said cam followers.
27. Apparatus of the character described, comprising a flexible cylinder and deflecting means for said cylinder including a deflector rod, constantly rotating cams adapted to operate said rod selectively in either deflecting or retracting direction, and means for placing said rod under the influence of said cams, said means including cam followers selectively slidable toward and from the cams and means for operating said cam followers, said last mentioned means including a constantly rotating cam.
28. Apparatus of the character described, comprising a flexible cylinder and deflecting means for said cylinder including a deflector rod, constantly rotating cams adapted to operate said rod selectively in either deflecting or retracting direction, and means for placing said rod under the influence of said cams, said means including cam followers selectively slidable toward and from the cams and means for operating said cam followers, said last mentioned means including a constantly rotating cam and a flexible connector between last mentioned cam and said cam followers.
29. Apparatus of the character described, comprising a flexible receptacle having the walls thereof formed of a plurality of sections arranged substantially edge to edge with the opposing edges of adjoining sections flexibly connected.
30. Apparatus of the character described comprising a deformable cylinder, and spray means within said cylinder, the cylinder and spray means having relative movement to provide contact of the spray with the entire circumference of the cylinder and the spray means being constructed and arranged to permit deformation of the cylinder without interference.
31. Apparatus of the character described comprising a flexible cylinder, means for flexing said cylinder, and submerged jets for directing a refrigerant against the inner surface of said cylinder, said cylinder and submerged jets having relative movement to provide contact by the jets of refrigerant with substantially the entire circumference of the cylinder.
32. The method of solidifying a fluid which consists in projecting a refrigerant in submerged jets upon one face of a flexible heat exchange diaphragm while maintaining the opposite face of said diaphragm exposed to the fluid to be solidified and subsequently flexing the diaphragm to remove the solidified fluid therefrom.
33. The method of freezing ice which consists in submerging in a liquid a receptacle having a deformable heat exchange wall, directing a refrigerant by submerged jets upon the inside face of said wall to cause ice to be formed on the outer face thereof and causing the wall to be flexed to discharge the ice therefrom.
34. The method of freezing ice which consists in partially submerging a flexible receptacle in the liquid to be frozen, projecting a refrigerant by submerged jets upon the inner face of a portion of the wall of the receptacle in contact with said liquid until a coating of frozen liquid of sufficient thickness is formed on the outer face thereof and deforming the coated wall to cause the frozen liquid to become detached therefrom.
35. The method of freezing ice which consists in forming a layer of ice on a thin flexible heat exchange wall of a receptacle partially submerged in the liquid to be frozen by spraying a refrigerant upon the inside face of said wall while protecting other portions of the receptacle walls from contact with said refrigerant and flexing said wall to cause the formed ice to be disengaged therefrom.
36. The method of depositing a solid from a fluid which consists in projecting a heat exchange medium upon one face of a heat exchange diaphragm, and applying said fluid to the opposite face of said diaphragm, and subsequently automatically flexing the diaphragm at predetermined intervals to remove the product therefrom.
37. The method of depositing a solid from a fluid which comprises rotating a flexible cylindrical surface, projecting a fluid heat exchange medium by submerged jets against one side of said cylinder, and applying said fluid to the other side of said cylinder and subsequently flexing the cylinder from its normal configuration to loosen the solidified product therefrom.
38. In apparatus of the class described, in combination, a rotary cylinder formed from a flexible material which is a good heat conductor, deflecting means for said cylinder disposed adjacent the surfaces of said cylinder, and means for moving said deflecting means to deflect said cylinder in timed relationship to the rotation of the cylinder.
39. In apparatus of the class described, in combination, a rotary cylinder of flexible material having a high coefficient of heat transfer, deflecting means for said cylinder operable between a first position where substantially no deflection of the cylinder is produced, a second position in which the cylinder is deflected from its normal configuration, and means controlling the action of said deflecting means operable in timed relationship to the rotation of the cylinder.
40. In apparatus of the class described, in combination, a flexible cylinder adapted to be deformed to loosen a solid deposited on the surface thereof, means for projecting a heat exchange fluid onto a surface of said cylinder to provide a rapid flow of said fluid over said surface whereby a higher degree of heat transfer is obtained, and said cylinder and said projecting means having relative movement therebetween, to apply said rapidly moving film over the entire circumference of the cylinder.
41. In apparatus of the class described, in combination, a flexible heat transfer cylinder, a plurality of longitudinal spray members arranged about the axis of the cylinder closely adjacent the interior surface of said cylinder, said spray members being adapted to project a refrigerant upon said surfaces, and means for supporting said spray members, whereby said spray members may support said cylinder in the event of the collapse of said cylinder.
42. In apparatus of the class described, in combination, a rotatable cylinder formed from a flexible material, heads for said cylinder, means for reducing the effective heat transfer coefficient of said heads, and said means comprising a plurality of flexible insulating disks attached to the heads.
43. In apparatus of the class described, in

- combination, a rotary heat transfer cylinder, means for circulating a heat exchange fluid through said cylinder, and means near the top of said cylinder for venting entrapped gases from the interior of said cylinder for the purpose specified.
44. In apparatus of the class described, in combination, a rotatable cylinder formed from a flexible material having a high coefficient of heat transfer, said cylinder being immersed in a liquid, means for circulating a refrigerant fluid through the cylinder, said means including a pressure regulating means for maintaining a predetermined hydrostatic head on the interior of the cylinder, and additional means for preventing siphoning of said refrigerating fluid from said cylinder.
45. In apparatus of the class described, in combination, a cylinder formed from a flexible material having a high coefficient of heat transfer, and said cylinder being formed from a plurality of metal strips joined by flexible non-metallic strips.
46. In apparatus of the class described, in combination, a cylinder formed from a flexible material having a high coefficient of heat transfer, said cylinder being formed from a plurality of metal strips circumferentially joined by non-metallic strips, deflecting means disposed within said cylinder, and means also on said cylinder adapted to serve as tracks for said deflecting means.
47. In apparatus of the class described, in combination, a cylinder formed from a flexible material having a high coefficient of heat transfer, stub-shafts connected with the opposite ends of said cylinder, said stub-shafts being adapted to rotate said cylinder, a synchronized drive for driving both of said shafts together, and adjusting means for adjusting the driving relation between said shafts and said driving means.
48. In apparatus of the class described, in combination, a flexible cylinder, deflecting means for deflecting said cylinder, and means for operating said deflecting means controlled by the operation of said cylinder.
49. In apparatus of the class described, in combination, a flexible cylinder and deflecting means for said cylinder including a deflector operating member, constantly rotating cams adapted to operate said member selectively in either deflecting or retracting direction and means for placing said member under the influence of said cam, said means including cam followers selectively movable toward and away from the cams and means for operating said cam followers.
50. In apparatus of the class described, in combination, a flexible cylinder, means for flexing said cylinder, and fluid projecting means within said cylinder, for effecting a rapid flow of the projected fluid over a surface of said cylinder, whereby the heat transfer between said cylinder and said fluid is increased.
51. The method of locally freezing a liquid which consists in submerging a receptacle having a deformable heat exchange wall in said liquid, directing a refrigerant upon the inside face of said wall, whereby the liquid adjacent the outside face of the wall is rapidly cooled and solidified thereon, and causing the wall to be flexed to discharge the frozen product therefrom, and said refrigerant being directed against said inside face to provide a rapid flow of the refrigerant over said face, whereby the heat exchange between said wall and refrigerant is increased.
52. The method of solidifying a solid from a fluid which comprises forming a layer of the solid on a flexible submerged heat exchange diaphragm, and automatically flexing said diaphragm at predetermined intervals to loosen the solid therefrom.
53. In apparatus of the class described, in combination, a rotary cylinder formed from a flexible material having a high coefficient of heat transfer, deflecting means for deflecting said cylinder including a deflector rod, and means for automatically operating said rod at predetermined intervals, said means being adjustable to change the period and/or duration of said intervals.
54. In apparatus of the class described, in combination, a rotatable cylinder formed from a flexible material having a high coefficient of heat transfer, said cylinder being mounted on sub-shafts, driving means for said shafts to rotate said cylinder, and a hollow shaft through said sub-shafts; spray means connected with said hollow shaft, and located interiorly of said cylinder, one end of said hollow shaft being adapted to serve as an inlet for a refrigerant to be sprayed through said spraying means, and the other end of said hollow shaft being adapted to serve as an outlet for said refrigerant, and insulating means for separating the unsprayed refrigerant from the sprayed refrigerant, whereby the over-all efficiency of the said apparatus is increased.
55. In apparatus of the class described, in combination, a cylinder having a thin flexible endless wall, heads for the ends of said cylinder and flexible aprons for connecting the ends of said cylinder wall to their respective heads whereby the wall may be flexibly supported by said heads, and have radial movement with respect to the heads.
56. In apparatus of the class described, in combination, an endless flexible sheet, supporting means for said sheet rotatable about a fixed axis, and means for flexibly connecting at least one of the edge portions of said sheet to said means to permit radial movement between said edge portions and said supporting means, whereby the endless flexible sheet is flexibly supported by said means and may have radial movement with respect to said means.
57. In apparatus of the class described, in combination, an endless flexible sheet, supporting means for said sheet, and means for flexibly connecting at least one of the edge portions of said sheet to said means to permit radial movement between said edge portions and said supporting means, whereby the endless flexible sheet is flexibly supported by said means and may have radial movement with respect to said means, said supporting means also affording a drive for imparting travelling motion to said endless flexible sheet.
58. In apparatus of the class described, in combination, an endless flexible sheet, supporting means movable about an axis, and means for flexibly connecting at least one of the edge portions of said sheet to said means to permit radial movement between said edge portions and said supporting means, whereby the endless flexible sheet is flexibly supported by said means and may have radial movement with respect to said means, said supporting means also affording a drive for imparting travelling motion to said endless flexible sheet, and ways for causing the sheet to travel over a curved path having a straight line cross section taken along its width.
59. In apparatus of the class described, in combination, an endless flexible sheet, supporting means rotatable about a fixed axis, and means for

- flexibly connecting at least one of the edge portions of said sheet to said means to permit radial movement between said edge portions and said supporting means, whereby the endless flexible sheet is flexibly supported by said means and may have radial movement with respect to said means, said supporting means also affording a drive for imparting travelling motion to said endless flexible sheet, said means for flexibly connecting said supporting means and said sheet comprising a flexible heat insulating material.
60. In apparatus for congealing fluid in strips, in combination, an endless flexible belt comprising spaced peripheral portions having a relatively high coefficient of heat transfer, separated by peripheral portions having a relatively low coefficient of heat transfer, means for applying fluid to be congealed to one side of said belt, means for removing heat from the other side thereof, and means for flexing said belt to remove the congealed strips therefrom.
61. Apparatus of the character described, comprising an endless flexible belt formed from a plurality of endless flexible sections arranged in edge to edge spaced relationship, and means for flexibly connecting contiguous edge portions of adjoining sections.
62. Apparatus of the character described, comprising an endless flexible belt formed from a plurality of endless sections arranged in edge to edge spaced relationship, and means for flexibly connecting contiguous edge portions of adjoining sections; the side edge portions of said belt having flexible aprons secured thereto and a head for closing each side of said belt, the respective aprons being secured to the respective heads whereby the belt may be flexibly driven by said heads.
63. Apparatus of the character described, comprising an endless flexible freezing surface formed of a plurality of endless panels arranged in spaced edge to edge relationship, re-enforced rubber strips secured to adjacent edge portions of adjacent panels to connect flexibly said panels, and the portions of said strips actually in contact with said panels being appreciably thicker than the proportions bridging the space between said panels.
64. The method of removing acrystallized liquid from a surface which consists in cutting adjacent troughs in said crystallized liquid and then cutting the crests left between said troughs.
65. Apparatus of the character described, comprising in combination, a tank for a liquid to be frozen, an endless belt movably mounted on a shaft, and at least partially submerged in the liquid in the tank, opposite sides of said tank having cut-out U shaped portions 30—30 for the reception of said shaft, and vertical bearing supporting plates 34—34 for supporting said shaft and belt, and means for securing said plates in position to close said U shaped cut-out portions.
66. In apparatus of the class described, in combination, an endless flexible belt, heads for closing the ends of said endless flexible belt, and flexibly connected to said belt, said heads being adapted to impart motion to said endless flexible belt, and a synchronized drive for driving both of said heads together, and adjustable means for adjusting the driving relationship existing between said heads and driving means.
67. In apparatus of the class described, in combination, a heat exchange cylinder mounted for movement about a fixed hollow shaft, spiders adjustably mounted inside the cylinder, and spray means mounted on said spiders for directing jets of a refrigerant against the interior of said cylindrical surface; means for supplying the refrigerant to said spray means through one end of said shaft, and means for removing the spent refrigerant from the other end of said shaft.
68. In apparatus of the class described, in combination, a heat exchange cylinder mounted for movement about a fixed hollow shaft, spiders adjustably mounted on said shaft inside the cylinder, and spray means mounted on said spiders for directing jets of a refrigerant against the interior of said cylindrical surface, each spray means including a foraminous sheet extending the length of said cylinder and backed by a header for conducting the refrigerant to said foraminous plate, and means for insulating said header from spent refrigerant in said cylinder; means for supplying the refrigerant to said spray means including means for supplying it to one end of said shaft, and flexible means connecting said shaft and spray means; and means for removing the spent refrigerant from the other end of said shaft.
69. In apparatus of the class described, in combination, a heat exchange cylinder immersed in a body of water, means for circulating a refrigerating liquid through the cylinder including a stand-pipe for maintaining a pre-determined head in the interior of the cylinder, and a check valve in said stand-pipe allowing the flow of fluid into said stand-pipe but preventing the flow of fluid therefrom.
70. Apparatus of the character described, comprising in combination, an endless flexible belt, means for causing said belt to travel about one path, means for causing said belt to travel about another path, and means for causing said last named means to act periodically.
71. In apparatus of the class described, in combination, a flexible cylinder, deflecting means mounted within said cylinder, and means for causing relative motion between said cylinder and deflecting means, and means for causing said deflecting means to deflect the walls of said cylinder, the operation of said last named means being timed by the relative movement between said cylinder and deflecting means.
72. In apparatus of the character described, a flexible endless belt, ways disposed within said belt, and circumferential strips located on the interior of said endless belt forming tracks for supporting said belt on said ways.
73. In apparatus of the class described, in combination, in a flexible cylinder, deflecting means for deflecting the walls of said cylinder, and means for operating said deflecting means controlled by the relative movement between said deflecting means and said cylinder.
74. In apparatus of the class described, in combination, a flexible cylinder, deflecting means for deflecting said cylinder and means for automatically operating said deflecting means at predetermined intervals, said means being adjustable to change the period and/or time of said intervals.
75. In apparatus of the class described, in combination, a flexible cylinder, a shaft running through said cylinder, movable ways mounted on said shaft in said cylinder for radial movement with respect to said shaft, said ways being adapted to determine the path over which the cylinder wall travels.
76. In apparatus of the class described, in combination, a flexible cylinder, a shaft running through said cylinder, guide means in said cylinder,

- inder, and means for mounting said guide means on said shaft for radial movement with respect to said shaft, said guide means being adapted to determine the path through which the cylinder wall travels, and means for moving said guide means toward and away from said shaft to change the path over which said cylinder wall travels as it moves about said shaft.
77. In apparatus of the class described, in combination, a flexible cylinder movably mounted on a shaft running through said cylinder, ways in said cylinder for determining the path of travel of the wall of said cylinder, means for mounting said ways on said shaft for radial movement with respect to said shaft, said mounting means including guides secured to and radially extending from said shaft, slides mounted on said guides connected to and supporting said ways, and toggle mechanism connected with said slides for radially moving said slides with respect to said shaft.
78. A method of depositing a solid from a fluid which consists in applying said fluid to one side of a flexible heat exchange diaphragm, removing heat from the other side of said diaphragm by means of a heat exchange medium and subsequently automatically flexing said diaphragm uniformly across its width at predetermined intervals to remove the product therefrom.
79. A method of forming a solid from a fluid which consists in applying said fluid to one face of a diaphragm, maintaining spaced peripheral areas of said diaphragm at a relatively low temperature and sufficient to crystallize the fluid applied thereto, and subsequently flexing the diaphragm to remove the product therefrom.
80. The method of producing ice in strips which comprises supplying the liquid to be frozen to one side of an endless flexible freezing surface having spaced peripheral heat conducting areas separated by non-heat conducting areas, removing heat from the other side of said freezing surface, and flexing said surface uniformly across the width of each heat conducting area to cause strips of ice frozen on said heat conducting areas to peel therefrom.
81. The method of producing a continuous strip of solidified fluid which comprises applying the fluid to one side of an endless flexible freezing surface, removing heat from the other side of said flexible freezing surface, and causing said endless flexible freezing surface to travel over a predetermined path of such a configuration as to allow the solidified fluid to remain on said endless flexible freezing surface over a predetermined portion of said path, but the remaining portion of said path being of such a configuration as to cause the solidified fluid to peel from the endless flexible freezing surface.
82. The process of manufacturing a free flowing substantially congealed ice product which consists in forming symmetrical sheets of ice, each sheet having a curved surface and being relatively thin in depth and having at least two edges symmetrical, and then subjecting each sheet to breakage whereby fragments having a degree of uniformity in size and shape are produced.
83. The process of manufacturing free flowing, substantially congealed, pieces of ice which consists in forming symmetrical sheets of ice, each sheet being relatively thin and having adjacent portions of at least one of its sides out of rectilinear alignment, causing each sheet of ice to be mechanically broken into fragments having a higher degree of uniformity in size and shape
- than fragments formed from non-symmetrical sheets subjected to the same conditions.
84. The process of manufacturing free flowing substantially congealed pieces of ice, which consists in supplying material from which the ice is formed to a moving ice-sheet-forming surface having adjacent portions out of rectilinear alignment, and capable of permanently imparting to the ice formed thereby a shape similar to the shape thereof, continuously removing the ice sheet formed from said surface and projecting it therefrom in successive sheets symmetrical with respect to each other and having sides with portions out of rectilinear alignment, and subjecting said sheets to breaking stresses and strains to cause said sheets to break into fragments of a higher degree of uniformity of size and shape than those formed by subjecting non-symmetrical sheets to the same conditions.
85. A step in the process of manufacturing ice comprising shaping the ice upon a moving curved surface and projecting the shaped ice therefrom in the form of elongated relatively thin sheets having a curvilinear surface and substantially parallel edges, said sheets being susceptible of subsequent breakage to form ice fragments of a size particularly adapted for commercial use.
86. Process of manufacturing ice which consists in supplying material from which the ice is formed to at least one moving curved surface, substantially constant in its width, separating and projecting said strip from said moving surface in the shape of a curved strip having a free end.
87. In combination, a cylinder having an endless flexible wall, flexible aprons secured to the respective edge portions of said wall, and power driven driving means secured to said aprons for imparting rotational movement to said cylinder.
88. In combination, a cylinder having a flexible wall, a flexible apron secured to each edge portion of said wall with a fluid-tight connection, and power driven driving means secured to said aprons with fluid-tight connections for imparting rotational movement to said cylinder.
89. An apparatus of the class described, comprising, in combination, a relatively elongated and curved ice-shaping surface whereby elongated and curved shapes of ice may be formed by said ice-shaping surface, receptacle means for holding a supply of material to be converted into ice shapes, means for supplying said material from said source to said surface, ice cake-forming means cooperative with said surface for converting said material so supplied into ice shapes, means for regulating the apparatus to determine the thickness of the ice shape, and means coating with said ice-shaping surface to cause the complete removal of the ice therefrom.
90. An apparatus for the production of ice shapes comprising, in combination, a receptacle for a supply of material to be made into ice shapes, an ice-shaping member having an ice-shaping surface adjacent portions of which are out of rectilinear alignment with each other; means for supplying successive amounts of said material to said member, means for transforming the material into solid form and causing the ice shape thus formed to conform substantially to the contours of the ice-shaping surface of said member, means for uniformly removing said ice shapes from said ice-shaping surface, and means cooperative with said member to control the thickness of the ice shapes produced by said apparatus.
91. A method of freezing liquids which consists in supplying a freezable liquid to a flexible de-

formable freezing surface, removing heat from predetermined spaced areas of said freezing surface to cause said freezable liquid to freeze on said surface in strips, and deflecting the freezing 5 surface to remove the strips of frozen liquid therefrom.

92. An apparatus for manufacturing regular shapes of ice, comprising, in combination, a source of liquid to be converted into ice shapes, an ice-forming member having an ice-shaping surface, means for supplying the liquid to said ice-forming member, and means for flexing said surface into a shape to cause the ice to separate therefrom across the entire width of said ice-shaping 10 surface.

93. Apparatus of the character described comprising a flexible cylinder, deflecting means for progressively flexing said cylinder, automatic means for periodically moving said deflecting 15 means into flexing position, means super-imposed on said automatic means for holding said deflecting means in flexing position when so desired, and manually operable means for shifting the control of the deflecting means from said automatic means to said super-imposed means and vice versa, from said super-imposed means to said 20 automatic means.

94. The method of manufacturing curved ice which comprises the steps of supplying liquid 25 to be frozen to a flexible freezing cylinder, and

of progressively flexing said cylinder uniformly across its entire width to cause the sheet of ice formed thereon to peel therefrom across its entire width. 5

95. Apparatus comprising in combination a movable ice-shaping member having an ice-shaping surface movable about a closed path having adjacent portions out of rectilinear alignment, means for supplying material to be converted into ice shapes to said ice-shaping surface, means 10 co-operating with said surface for converting said material into a solid form conforming to the contours of said surface, and means for completely removing said ice from said surface in the shape in which it was formed as said surface 15 moves past a point in said path.

96. Apparatus for making ice, in combination, a rotary cylinder, means for refrigerating the inside of said cylinder, means for supplying water to be frozen to the exterior of said cylinder, 20 whereby as said cylinder rotates ice forms thereon, means for progressively changing the physical character of this cylinder uniformly across its entire width without producing a corresponding change in the ice formed thereon to cause 25 a loosening of the ice from the cylinder, and means for conducting said ice away from said cylinder.

CROSBY FIELD. 30
